UNITED STATES PATENT OFFICE.

GEORGE A. KNEESE, OF SOUTH SAN FRANCISCO, AND ROBERT A. KLASSEN, OF SAN FRANCISCO, CALIFORNIA.

CURB-PLATE.

1,195,689.

Specification of Letters Patent. Patented Aug. 22, 1916.

Application filed October 25, 1915. Serial No. 57,690.

To all whom it may concern:

Be it known that we, GEORGE A. KNEESE, of South San Francisco, county of San Mateo, State of California, and ROBERT A. KLASSEN, of the city and county of San Francisco, State of California, citizens of the United States, have invented new and useful Improvements in Curb-Plates, of which the following is a specification.

10 This invention relates to a curb bar or armor plate for concrete structures, such as street curbs and the like.

One of the objects of the present invention is to provide a simple, substantial cheaply manufactured curb bar or plate, provided with means formed integral therewith for keying or tying it to the concrete structure which it protects, in such a manner that it forms an integral part therewith when the 20 concrete sets.

Another object of the invention is to so construct the plate that it may be built in or placed in position within the form before the concrete is poured, and furthermore, to bend or shape the plate and key members to prevent formation of air pockets or spaces that can not be tamped.

Further objects will hereinafter appear. The invention consists of the parts and 30 the construction and combination of parts, as hereinafter more fully described and claimed, having reference to the accompanying drawings, in which—

Figure 1 is a cross section of a street curb, showing the application of the invention. Fig. 2 is a side elevation of a curb plate. Fig. 3 is a plan edge view of same. Fig. 4 is a view similar to Fig. 3 showing the key members bent at angles opposite to each 40 other.

Referring to the drawings in detail, A indicates a plate, the upper edge of which is bent, as at 2 to form a curved face which partly covers the outside corner of the curb, indicated at B. This plate may be made in lengths, such as may be required and may be formed by rollers or like machinery, not here shown.

For the purpose of locking the plate to 50 the concrete of which the curb B is constructed, a plurality of inter-spaced key

members 3 have been provided. These are formed by cutting or slotting the face or side of the plate, as indicated at 4 and the metal thus cut is preferably bent in to 55 assume an angle with relation to the face of the plate, as is indicated in Fig. 3, or the tangs or key members 3 may be bent on angles to the face of the plate, so that they will assume positions opposite to each other, 60 as indicated at 5, in Fig. 4.

For the purpose of further insuring a perfect lock between the concrete and the plate, a hook-like bend 6 may be formed on the inner end of each tang or key 3. A 65 curb armor or plate constructed as here shown may be built or set in a wooden form before the concrete is poured and the shape of it is such that no pockets or spaces are formed into which the concrete will not 70 readily flow. The curve 2 on the upper edge of the bar is furthermore such that no air can possibly pocket under same. A perfect contact between the concrete and the plate is thus made at all points and no time 75 is lost in forcing the concrete under ledges or projecting parts thereof, such as often is necessary with other forms of bars commonly used.

The materials and finish of the bar may 80 otherwise be such as the judgment and experience of the manufacturer may dictate.

We wish it understood that various changes in form, proportions and minor details of construction may be resorted to 85 within the scope of the appended claims and that we do not wish to limit ourselves to the specific design and construction here shown.

Having thus described our invention, what 90 we claim and desire to secure by Letters Patent is—

A curb plate comprising, in its entirety, a metal sheet bent to provide a straight lower portion and an adjoining curved 95 upper portion terminating in an upwardly inclined plane so that trapped air thereunder will have a continuous upward passage to the exterior; and a key member struck out horizontally from the curved 100 upper portion at a point immediately adjoining the straight lower portion whereby

said key will extend at a downward incline from the curb plate into the concrete curb in which it is embedded; said key, by being struck out from the plate at the lower part 5 of the curved upper portion, providing an opening immediately above the straight lower portion for liberating entrapped air.

In testimony whereof we have hereunto

set our hands in the presence of two subscribing witnesses.

GEORGE A KNEESE.
ROBERT A. KLASSEN.
